UNITED STATES PATENT OFFICE.

JOSEPH A. TREGO, OF PHILADELPHIA, PENNSYLVANIA.

DESIGN FOR A BRUSH.

60,431.

Specification for Design. Patented Feb. 14, 1922.

Application filed June 25, 1921. Serial No. 480,447. Term of patent 8½ years.

To all whom it may concern:

Be it known that I, JOSEPH A. TREGO, a citizen of the United States, residing in the city and county of Philadelphia, State of Pennsylvania, have invented a new, original, and ornamental Design for Brushes, of which the following is a specification, reference being had to the accompanying drawing, forming part thereof.

The figure is a perspective view of a brush showing my new design.

I claim:

The ornamental design for a brush, as shown.

JOSEPH A. TREGO.
